UNITED STATES PATENT OFFICE.

WALTER A. PECK AND RICHARD A. BRIGHT, OF PROVIDENCE, RHODE ISLAND; SAID BRIGHT ASSIGNOR TO SAID PECK.

MACHINE FOR FORMING AND ROLLING CIGARS.

SPECIFICATION forming part of Letters Patent No. 451,738, dated May 5, 1891.

Application filed April 19, 1890. Serial No. 348,692. (No model.)

To all whom it may concern:

Be it known that we, WALTER A. PECK and RICHARD A. BRIGHT, citizens of the United States, residing at Providence, in the State of Rhode Island, have invented a new and useful Improvement in Machines for Forming and Rolling Cigars, of which the following is a specification.

Our invention consists in the employment 10 of two sets of forming-rolls which extend in opposite directions and lap by each other to form a rolling-chamber, whereby cigars having extremely-tapered head and tuck ends can be readily made.

15 Figure 1 represents a front elevation of a cigar-machine embodying our invention, the springs which serve to hold the rolls in closed position being removed. Fig. 2 represents an end elevation of the same. Fig. 3 represents 20 a vertical section taken in the line xx of Fig. 1. Fig. 4 represents a vertical section taken in the line yy of Fig. 1. Fig. 5 represents a longitudinal section of a tapering flexible roll, such as may be employed in carrying out our 25 invention. Fig. 6 represents a top view of the machine. Fig. 7 represents a vertical section taken in the line xx of Fig. 6. Figs. 8 and 9 represent a vertical section, as in Fig. 7, and show different positions of the opening-rolls. Fig. 10 is a detail elevation from 30 the front side of the machine, showing the forming-rolls which are attached to the fixed standards. Fig. 11 is a detail elevation from the front side of the machine, showing the 35 forming-rolls which are attached to the movable jaws.

In the accompanying drawings, A represents the bed-plate of the machine, which is provided with a longitudinally-extending 40 raised portion b . The foot h of the standards B B', which serve to support the stationary forming-rolls, is provided with a groove a , which fits over the raised portion b of the bed, and is also provided with a slot c , adapted 45 to receive the fastening-screw d , so that the standards B B', either one or both, may have a limited adjusting movement along the bed-plate A.

The standards B B' are each provided with 50 the opening and closing jaws C C', respectively, the said jaws being connected to each

other by means of the rod D, which is provided at its opposite ends with the adjusting-nuts $e e$, by means of which the relative distance between the jaws C C' can be changed 55 as desired, and upon the rod D is secured the ironing-plate E, which serves to smooth out the binder or wrapper as it is being wound onto the inclosed mass of fillers or bunch.

The connected jaws C C' are prevented 60 from movement endwise of the machine by means of the heads F F', which are attached to the outer side of the standards B B', respectively.

The jaws C C' are provided with the cylindrically-formed fulcrums ff , which are adapted to rest and turn in the corresponding bearings $g g$ in the standards B B', and the connected jaws C C' are held in position in the bearings $g g$ by means of the curved springs 70 G G, which are attached to the foot h of the standards B B' and act against the stud H, attached to the arm i of the jaws C C'.

The tapered forming-rolls 1 and 2 are supported by means of the standard B, and the 75 roll 3 of the same set is supported by the accompanying jaw C at one end of the machine.

The rolls 4 and 6 are supported by the jaw C', and the roll 5 is supported by the accompanying standard B', the said rolls 4, 5, and 80 6 also forming a set, the ends of which are arranged to lap by the ends of the rolls of the opposite set 1, 2, and 3, as shown in the drawings, thus forming a rolling-chamber A', 85 which can be reduced in diameter or tapered at either or both of its ends, as desired, and with our improved lapping arrangement of the sets of forming-rolls we can roll a bunch which is completely pointed at both ends 90 and have the surface speed of the bunch throughout its whole length practically equal to that of the forming-rolls, which result has not been accomplished in any cigar-rolling machine heretofore constructed, so that on 95 this account cigars of extreme tapering shape have heretofore been rolled by hand. The tapering rolling-chamber A' will also be adapted to roll loose fillers without a tendency to twist the same, so that the formation 100 of properly-tapered cigar-bunches will be greatly facilitated. The rolls of each set are

- geared to rotate in the same direction, as in ordinary binding and wrapping machines, and in carrying out our invention rolls of any suitable form or construction may be employed, an example of the employment of the well-known spirally-constructed flexible rolls being shown in the drawings 1, 5, and 6 as a sufficient exemplification of the principle involved in our invention.
- 10 The forming-rolls of the separate sets are driven simultaneously from the shaft I, which has its bearing in the standard B, the said shaft being provided with a gear j, which engages with the intermediate gear k, placed loosely upon the stud l, the said intermediate gear being made to engage with the gear m upon the shaft K, which has its bearings in the standards B B', and at the opposite end of the shaft K is placed the gear m', which engages with the intermediate gear k', the said gear being arranged to turn loosely upon a stud l' and engages with the gear j' upon the shaft I', which shaft has its bearing in the standard B', and upon the inner ends 25 of the oppositely-arranged shafts I I', which revolve in the same direction, are placed the gears n n', the gear n being made to engage with the gears o o of the set of forming-rolls 1 2 3 and the gear n' to engage with the 30 gears o' o' o' of the opposite set of forming-rolls 4 5 6, as shown in Figs. 3 and 4.

Connection may be made from the rod D, which connects the opposite jaws C C', by means of the connecting-rods p p to arms q, 35 attached to a rock-shaft J, which is to be held in suitable bearings, and from one of the arms q a connecting-rod r may extend to a treadle, by means of which the movable forming-rolls of the opposite sets can be operated to open and close the rolling-chamber A', the downward movement of the rod r serving to open the chamber in an upward direction to receive the cigar-fillers or the cigar-bunch, as shown in Fig. 9, and the 40 opposite upward movement of the rod r serving to open the chamber A' in a downward direction to discharge the bunch, as shown in Fig. 8, the said chamber being maintained in a closed condition for rolling the fillers or bunch

by means of the curved springs G G, as shown 50 in Fig. 7, the opening-roll 3 being attached to and operated from the jaw C, (shown in Figs. 7 and 8,) the accompanying rolls 4 and 6 being attached to and operated from the jaw C', so that in any case at least one of each set of 55 oppositely-directed lapping rolls will be moved to open the rolling-chamber.

By adjusting the standards B B' and their accompanying jaws C C' nearer to or farther from each other the rolling-chamber A' will 60 be lengthened or shortened and changed as to its contour, so that the machine can be readily adjusted for making cigars of different lengths and various shapes.

We claim as our invention—

1. The combination of two sets of forming-rolls and driving mechanism therefor, said rolls extending in opposite directions from their driven ends and lapping by each other to form a rolling-chamber, substantially as 70 described.

2. The combination of two sets of forming-rolls tapered at their forward ends and driving mechanism therefor, said rolls extending in opposite directions from their driven ends 75 and lapping by each other to form an oppositely-tapered rolling-chamber, substantially as described.

3. The combination of two sets of forming-rolls extending in opposite directions from 80 their driven ends and lapping by each other to form a rolling-chamber, driving mechanism for said rolls, and means for moving one or more rolls of each set to open the rolling-chamber, substantially as described. 85

4. The combination of two sets of forming-rolls tapered at their forward ends and lapping by each other to form a rolling-chamber, driving mechanism for said rolls, and means for adjusting each set of rolls lengthwise of 90 the other to change the length or shape of the rolling-chamber, substantially as described.

WALTER A. PECK.
RICHARD A. BRIGHT.
